DUST COLLECTOR

Raymond Little, Decatur, Ind.

Application October 26, 1940, Serial No. 363,039

4 Claims. (Cl. 183—86)

This invention relates to a dust collector for freeing air of dust and is especially adapted for use in grain grinding mills and similar places where there is a constant danger of explosions from dust-laden air. The primary object of the invention is the provision of a device of this character in which dust-laden air may be forced and caused to travel in cyclone fashion to bring about separation of the air and dust and permit the dust to gravitate out of the device for collection while the air may pass upwardly and outwardly substantially free of dust.

Another object of the invention is the provision of adjustable baffles for regulating the flow of air upwardly and outwardly of the device to assist in removing dust from the air and are regulated in accordance with the amount of dust which may be in the air as said air leaves the device.

With these and other objects in view, the invention consists in certain novel features of construction, combination and arrangement of parts to be hereinafter more fully described and claimed.

For a complete understanding of my invention, reference is to be had to the following description and accompanying drawings, in which

Figure 1 is a side elevation illustrating a dust collector constructed in accordance with my invention.

Figure 2 is a top plan view illustrating the same.

Figure 3 is a sectional view taken on the line 3—3 of Figure 1.

Figure 4 is a vertical sectional view illustrating the interior construction of the dust collector and the specific arrangement of the baffles.

Figure 5 is a fragmentary side elevation illustrating an operating lever for the baffles and the means of securing the same in adjusted positions.

Referring in detail to the drawings, the numeral 5 indicates an outer casing including a cylindrical portion 6 and a substantially funnel-shaped portion 7 providing a discharge neck 8 for dust. The upper end of the cylindrical portion 6 is closed by a top wall 9 and connected with the interior of the casing and formed on the side thereof adjacent the top wall is an inlet pipe 10. This pipe may be connected in any suitable manner to a grain grinding machine so that the dust-laden air forced from the machine may pass directly into the casing 5.

Arranged centrally of the casing 5 is a tubular sleeve 11, the lower end of which termi-

nates at the beginning of the funnel-shaped portion 7 while the upper end terminates in a plane above the top wall 9.

5 A substantially conical shaped deflector 12 surrounds a portion of the sleeve 11 and is formed on the latter and spaced from the walls of the cylindrical portion 6 of the casing. The deflector 12 is located below the inlet pipe 10 so that on the dust-laden air entering the casing it is caused to travel downwardly in a swirling motion into the funnel-shaped portion 7 where the dust settles by gravitation and passes outwardly of the outlet neck 8 and may be collected in a suitable collection means connected to said neck, while 10 the air rises upwardly through the sleeve 11 and escapes from the upper end thereof substantially free of dust.

Struck-out portions 13 are formed on the substantially conical shaped deflector to assist in 20 causing the air to travel in a swirling motion, and to aid in the separation of the dust from the air by catching dust and directing it into the deflector where it may gravitate into the funnel-shaped portion of the outer casing 5 for discharge therefrom. However, should some of 25 said dust be caught in an upwardly flowing stream of air it may escape by way of the struck-out portions 13 and become merged into the incoming flow of dust-laden air for recirculation 30 therewith.

A plurality of superimposed and staggeredly arranged baffles 14 are formed on the inner walls of the sleeve and depend downwardly and spaced from each other so that the air rising must 35 travel in a serpentine path.

The baffles are provided with opening 15 controlled by hinged dampers 16. The dampers 16 are located under the baffles and the lowermost dampers are connected to the uppermost dampers by links 17 while links 18 are pivotally connected to the uppermost dampers and are pivoted on a member 19 secured to a shaft 20 journaled in the upper portion of the sleeve and to 40 which a hand lever 21 is connected. Associated with the hand lever is an indicator plate 22 bearing suitable indicia to indicate the position of the dampers in accordance with the position occupied by a pointer or indicator 23 forming a portion of the attached end of the handle 21. The indicator plate 22 has an arcuate slot 24 through which extends a bolt 25 of the hand lever 21. A wing nut 26 is turned onto the bolt 45 to engage the hand lever and thereby bring about a binding of the bolt on the indicator plate 50 55.

for releasably securing the hand lever in its adjusted position.

It is to be understood that the links 17 are pivotally connected to their respective dampers.

Arranged above the upper end of the sleeve 11 and spaced therefrom is a hood 27 including a conical shaped member 28 and an inverted conical shaped member 29. The hood is supported by legs 30 fastened on the sleeve. The purpose of the hood is to deflect the air and spread the same in various directions as it leaves the upper end of the sleeve substantially free of dust.

The flow of air through the sleeve may be varied by varying or changing the position of the dampers with respect to the baffles for the purpose of increasing and decreasing the action of the baffles on the air. The adjustment of the dampers is made in accordance with the amount of dust that may be in the air as it leaves the upper portion of the sleeve.

The opening 30' provided in the sleeve 11 connects the interior of said sleeve with the outer casing 5 between the upper and lower groups of baffles. There will be a certain amount of dust rising in the sleeve 11 which strikes the baffles and is directed outwardly by said baffles and may escape through the opening 30' to meet the incoming dust-laden air for recirculation therewith. This arrangement, to a great extent, will prevent clogging of the baffles.

While I have shown and described the preferred embodiment of my invention, it will be understood that minor changes in construction, combination and arrangement of parts may be made without departing from the spirit and scope of the invention as claimed.

Having thus described my invention what I claim is:

1. A dust collector comprising a casing having an air inlet and a dust outlet, a sleeve rising centrally from said casing and providing an air outlet, means carried by said sleeve and arranged in said casing to deflect the air from the air inlet downwardly in the casing with a swirling motion to the lower end of the sleeve for passage upwardly therethrough, staggeredly arranged baffles arranged in said sleeve and having openings, hinged dampers carried by said baffles

for regulating the flow of air through the openings of the baffles, and means for adjusting the position of the dampers.

2. A dust collector comprising a casing having an air inlet and a dust outlet, a sleeve rising centrally from said casing and providing an air outlet, means carried by said sleeve and arranged in said casing to deflect the air from the air inlet downwardly in the casing with a swirling motion to the lower end of the sleeve for passage upwardly therethrough, staggeredly arranged baffles arranged in said sleeve and having openings, hinged dampers carried by said baffles for regulating the flow of air through the openings of the baffles, means connecting said dampers, an operating shaft journaled in said sleeve and connected with said means, and a releasably secured hand lever secured to said shaft.

3. A dust collector comprising a casing having an air inlet and a dust outlet, a sleeve rising centrally from said casing and providing an air outlet, means carried by said sleeve and arranged in said casing to deflect the air from the air inlet downwardly in the casing with a swirling motion to the lower end of the sleeve for passage upwardly therethrough, staggeredly arranged baffles arranged in said sleeve and having openings, hinged dampers carried by said baffles for regulating the flow of air through the openings of the baffles, means connecting said dampers, an operating shaft journaled in said sleeve and connected with said means, and a releasably secured hand lever secured to said shaft, and a hood arranged above and spaced from the upper end of the sleeve and mounted on the latter.

4. In a device of the character described, a casing having an air inlet and a dust outlet, a sleeve rising centrally from said casing and carried thereby, a substantially cone-shaped deflector mounted on said sleeve below the air inlet and spaced from the walls of the casing, staggered baffles arranged in said sleeve and having openings, hinged dampers for said openings, and an operating means connected to the dampers.

RAYMOND LITTLE.
